HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE.

SHEET CUTTING AND HANDLING MACHINE.

Application filed December 17, 1927. Serial No. 240,740.

In sheet cutting and handling machines where the sheets are cut on the square from a traveling web of thin or loosely woven fabric such, for instance, as burlap and where 5 the sheets are fed to a sheet taking means by a horizontally arranged endless carrier traveling at a slightly higher rate of speed than the speed of travel of the web, the first cut portion of each sheet will be fed ahead faster 10 by the carrier than the last cut portion and an inaccurate feeding of the sheet to the sheet taking means, results. To overcome this fault I provide means for squaring the sheets as they are being cut from the traveling 15 web and just as they reach their sheet taking means; said sheet squaring means comprising a horizontally disposed squaring bar around which the web is passed on its way to the sheet taking means, said squaring 20 bar overlying and disposed diagonally with respect to the sheet feeding carrier and co-acting therewith to cause one side of the web as it passes from the cutting means to the sheet taking means, to travel farther than the 25 other side of the web so that the leading edge of the web will be slightly distorted after it passes under the sheet squaring bar and will be brought back to its squared position parallel to the sheet taking means as the 30 sheet is severed from the web and just as the leading edge of the sheet is grasped by the sheet taking means.

A practical embodiment of my invention is represented in the accompanying drawings 35 as applied to a rotary printing press, in which

Fig. 1 represents in side elevation so much of a sheet cutting and handling machine as will give a clear understanding of my invention, the leading edge of the sheet being 40 shown grasped by the grippers of the sheet taking means and its tail end severed from the web.

Fig. 2 represents a horizontal section taken 45 in the plane of the line II—II of Fig. 1, looking in the direction of the arrows the leading edge of the web being shown in dotted lines in the position it assumes as it falls on to the endless tape carrier; in dot-and-dash 50 lines in the distorted position it assumes on its way from the squaring bar to the grippers of the sheet taking means before the sheet is severed from the web; and in double

dot-and-dash lines in the squared position which the leading edge of the sheet assumes 55 parallel to the grippers of the sheet taking means as the cutting of the sheet from the web has been completed and the sheet is grasped by the said grippers.

Fig. 3 represents an enlarged detail section showing one of the squaring bar adjusting side bars and its connection with the squaring bar and frame.

The machine frame is denoted by 1. The sheet taking means is herein shown as an impression cylinder 2 of a rotary printing press, said cylinder having a set of grippers 3 for taking the advance edge of the sheet. The traveling web 4 is shown as passing around the rolls 5 and 6 and the web feeding roll 70 7 and over the guide 8 to the sheet cutting means, which cutting means is herein shown as coacting rotary and stationary cutters 9 and 10, the rotary cutter being of the usual spiral type for imparting a shearing action 75 to sever the sheet on the square from the web. The means for feeding the sheets to the sheet taking means is herein shown as a horizontally arranged endless tape carrier 11 which is driven at a slightly greater rate 80 of speed than the speed of the traveling web.

A diagonally disposed horizontal squaring bar 12 is located between the said sheet feeding carrier and the sheet cutting means and the sheets pass around the bar between it and 85 the sheet feeding carrier in frictional engagement with the bar. The ends of this bar are loosely mounted on the forward screw-threaded ends of a pair of longitudinal side bars 13, 13, which side bars are, in turn, loosely 90 mounted in brackets 14, 14 and have screw-threaded engagement with brackets 15, 15 carried by the machine frame 1. The screw-threaded forward ends of these side bars are provided with nuts 16, 16, engaging the front 95 and back faces of the squaring bar for holding it in its proper adjustment on the side bars. The rear ends of these side bars are provided with suitable handles 17, 17 for manipulating them.

The operation of the machine is as follows:

The leading edge of the web when it strikes the endless tape carrier is parallel with the cut and with the grippers on the impression cylinder. As the web is passed under the 105 squaring bar by the tape carrier one side of

the web will take up the slack in the web back to the cutter 10, and will, due to the speed of the tape carrier 11, therefore be caused to travel a greater distance than the other side 5 on its way from the cutters to the sheet taking grippers because of the diagonal position of the squaring bar. This will cause the leading edge of the web to be brought out of parallelism with the cutter and the grippers before the sheet is severed from the web. The 10 tape carrier which travels at a speed faster than that of the web will bring the leading edge of the sheet back into parallelism with the sheet taking grippers just as the sheet is 15 being cut from the web and the squaring operation is completed just as the grippers grasp the sheet and the severing of the sheet is completed.

It will also be seen that the position and 20 the angularity of the squaring bar may be very accurately adjusted while the machine is in operation, by the manipulation of one or both of the longitudinal adjustable side bars.

It is evident that various changes may be 25 resorted to in the construction, form and arrangement of the several parts without departing from the spirit and scope of my invention; hence, I do not intend to be limited to the particular embodiment herein shown 30 and described, but

What I claim is:—

1. A sheet taking means, means for cutting sheets from a traveling web, sheet feeding means between said cutting and taking means 35 and sheet squaring means overlying and diagonally disposed with respect to the sheet feeding means and coacting therewith to square the leading edge of a sheet as it is being severed from the web for ensuring the presentation 40 of the leading edge of the sheet parallel to the sheet taking means.

2. A sheet taking means, means for cutting sheets from a traveling web, sheet feeding means between said cutting and taking means 45 and a sheet squaring bar overlying and diagonally disposed with respect to the sheet feeding means and coacting therewith to square the leading edge of a sheet as it is being severed from the web for ensuring the presentation 50 of the leading edge of the sheet parallel to the sheet taking means.

3. A sheet taking means, means for cutting sheets from a traveling web, sheet feeding means between said cutting and taking means, a sheet squaring bar overlying and diagonally disposed with respect to the sheet feeding 55 means and coacting therewith to square the leading edge of a sheet as it is being severed from the web for ensuring the presentation 60 of the leading edge of the sheet parallel to

the sheet taking means, and means for positioning and adjusting the angularity of said squaring bar.

4. A sheet taking means, means for cutting sheets from a traveling web, sheet feeding means between said cutting and taking means, a sheet squaring bar overlying and diagonally disposed with respect to the sheet feeding means and coacting therewith to square the leading edge of a sheet as it is being severed 65 from the web for ensuring the presentation of the leading edge of the sheet parallel to the sheet taking means, and means for positioning and adjusting the angularity of said squaring bar, including a pair of longitudinally 70 adjustable side bars.

5. A sheet taking means, means for cutting sheets from a traveling web, a horizontally arranged endless carrier between said cutting and taking means for feeding the sheets to 80 the sheet taking means, and a horizontally arranged sheet squaring bar overlying and diagonally disposed with respect to the endless carrier and coacting therewith to square the leading edge of a sheet as it is being severed 85 from the web for ensuring the presentation of the leading edge of the sheet parallel to the sheet taking means.

6. A sheet taking means, means for cutting sheets from a traveling web, a horizontally arranged endless carrier between said cutting and taking means for feeding the sheets to the sheet taking means, a horizontally arranged squaring bar overlying and diagonally disposed with respect to the endless carrier 95 and coacting therewith to square the leading edge of a sheet as it is being severed from the web for ensuring the presentation of the leading edge of the sheet parallel to the sheet taking means, and means for positioning and 100 adjusting the angularity of said squaring bar.

7. A sheet taking means, means for cutting sheets from a traveling web, a horizontally arranged endless carrier between said cutting and taking means for feeding the sheets to 105 the sheet taking means, a horizontally arranged squaring bar overlying and diagonally disposed with respect to the endless carrier and coacting therewith to square the leading edge of a sheet as it is being severed from the web for ensuring the presentation of the leading edge of the sheet parallel to the sheet taking means, and means for positioning and adjusting the angularity of said squaring bar, including a pair of longitudinally 110 adjustable side bars.

In testimony, that I claim the foregoing as my invention, I have signed my name this 14th day of December A. D., 1927.

HOWARD M. BARBER.
